UNITED STATES PATENT OFFICE.

ESTHER LEVINE, OF CHICAGO, ILLINOIS.

GARMENT HANGER.

Application filed August 21, 1925. Serial No. 51,653.

This invention relates to an improvement in garment hangers designed particularly for use with garments of delicate texture, and is particularly directed to a hanger with which the garment may be clamped at various determinate points to insure that the garment, when applied to the hanger, shall remain in fixed relation thereto until it is to be removed.

10 The improved garment hanger comprises a hanger proper and spring pressed clamping members cooperating therewith, the clamping members being relatively adjustable so that they may be moved to engage any desired portion of the garment, and cooperating with the hanger proper under sufficient stress to hold the garment in fixed relation without liability of marring or otherwise injuring the garment.

15 The invention is illustrated in the accompanying drawings, in which:—

Fig. 1 is a view in elevation of the improved garment hanger.

Fig. 2 is a plan of the same.

20 Fig. 3 is a transverse section through the clamping bars with a clamping plate shown thereon in elevation.

The improved hanger comprises a hanger proper including a bar 1 of the appropriate

25 arcuate form, and a fixed upstanding hook 2 by which the hanger may be supported from any convenient support. Clamping bars 3 of wire or the like are provided in

30 U-form to overlie the sections of the bar 1 on each side of the hook, the inner ends of the clamping bars being pivotally mounted upon a pin 4, fixed in the hook at an appropriate height. The clamping bars have

35 their side members 5 spaced apart a distance greater than the thickness or width of the bar 1, and have a clamping section 6 which extends substantially in parallelism to the bar 1, from the inner end of which clamping section the clamping bars incline up-

40 wardly as at 7 to their pivotal mounting on the pin 4. Clamping plates 8 are slidably mounted on the clamping sections 6 of the clamping bars, these plates being shaped to fit the upper edge of the clamping bar 1 and

45 have their end edges formed into sleeve-like terminals 9 to slidably embrace the side rods of the clamping section of each clamp-

ing bar. The lower or operative face of the clamping plates 8 may, if desired, be provided with any protective material, such as 55 cloth or the like. Spring strips 10 are secured to the hook above the clamping bars and project in both directions beyond the hook to overlie and bear upon the clamping bars to normally hold the latter in clamping 60 cooperation with the hanger bar 1.

In the use of the hanger with a garment having the usual neck and shoulder portions, the garment is centered on the hanger bar 1 and the clamps 8 adjusted on the 65 clamping bars to engage the shoulder portions of the garment and thus hold the garment in fixed relation to the hanger bar under the tension of the spring 10. In that type of garment having straps to represent 70 the shoulder portion, the straps are adjusted to the hanger bar and the clamping plates adjusted longitudinally of the clamping bars to engage the straps. Thus the garment of either form may be readily held by 75 the hanger in such fixed relation thereto as to prevent sliding or slipping of the garment in the handling or movement of the hanger, thereby preventing strain upon the garment or upon any ornaments applied 80 thereto.

I claim:—

A garment hanger comprising a rigid hanger bar, and a hook member secured to and projecting therefrom, clamping bars 85 pivotally mounted on the hook, each comprising parallel sections spaced apart a distance exceeding the width of the hanger bar, each clamping bar for a portion of its length from the free end being extended in 90 parallelism with the hanger bar, the remaining length of each clamping bar inclining upwardly from the hanger bar to the hook member, a slide on the free portion of each clamping bar including a plate to overlie 95 and bear directly upon the upper surface of the hanger bar, and spring members rigidly connected to the hook above the hanger bar and terminally bearing upon the inclined portion of each hanger bar to maintain the 100 slide in contact with the hanger bar.

In testimony whereof I affix my signature.

ESTHER LEVINE.
